UNITED STATES PATENT OFFICE

WILLIAM F. HELMOND, OF HARTFORD, CONNECTICUT, ASSIGNOR TO UNDERWOOD
ELLIOTT FISHER COMPANY, OF NEW YORK, N. Y., A CORPORATION OF DELAWARE

TYPEWRITING MACHINE

Application filed December 11, 1926. Serial No. 154,107.

This invention relates to the line-spacing of a typewriter platen and returning it by power to begin a new line.

Heretofore, a carriage-returning motor had to be large and powerful, in order for the motor to start up immediately and start the entire weight of the carriage and the carriage-returning mechanism, as well as the line-spacing mechanism. The motor, when energized, would at once put a heavy strain on all of the carriage-returning mechanism. As soon as the dead load was overcome, and the parts were set in motion, the carriage, by reason of the powerful motor, would be thrown back with great force. The power would be disconnected from the motor, and all the parts which were rotating at a high speed would be suddenly arrested, and thrown back to normal, ineffective positions.

15 This straining and slamming of the carriage-returning mechanism of the carriage tended to shorten its life, and was also annoying.

A feature of the present invention is to 20 overcome the above objections, and to so construct the parts that a cushioning effect will be obtained between the working parts of the carriage-returning mechanism and thereby lengthen their life and also the life of the typewriter. In the present invention, a comparatively small motor may be used, and as soon as said motor becomes energized through the depression of the carriage-return key in the keyboard, its initial slow motion is immediately utilized to connect the carriage-returning train of mechanism to the type-writer-carriage. The motor not yet rotating at a high speed, this mechanism will be operated without any jar or straining 25 of the parts, and as soon as said connection is made the motor will then be running at higher speed, at which time the heavy mass of carriage and other parts will be gradually set in motion, without any sudden strain or shock on the various parts of the mechanism. As soon as said inertia of the carriage is overcome, the operation of the line-spacing mechanism will become effective, at which time the motor will be delivering its 30 full power to the connected train of mecha-

nism. Upon further return of the carriage, the line-spacing mechanism is operated. Hence the carriage is returned with a comparatively small motor, thus reducing the jar of the returning carriage.

Just prior to the carriage completing its return movement, the electric switch is broken, and the motor immediately loses its 35 rotating power.

In the present invention, the parts are not 40 slammed back to normal position, but tend to cooperate with one another to produce a cushioning effect in the returning of said parts to normal position.

The motor is mounted at the rear of the 45 typewriting machine, and drives a worm and worm-wheel to propel the carriage. A clutch connects a carriage-return rack and pinion with the motor.

A finger-piece at the keyboard controls an 50 arm of an electric switch, said arm being thrown into a circuit-making position by a spring which is controlled by a pawl that is so connected to the finger-piece that varying blows upon the finger-piece result in the 55 same action of the switch-arm, energizing the motor.

The worm-shaft of the motor-drive effects 60 an engagement of the clutch-members, whereupon the carriage-return rack first effects the line-spacing, and then the return of the carriage. Means are carried by the carriage to throw out the switch-arm at the completion of the return of the carriage, or 65 at any intermediate position.

The mechanism is arranged to be readily 70 attached to a standard Underwood typewriting machine with a minimum of changes and additions.

A circuit maker and breaker, in the form 75 of a swinging contact-arm, constitutes a part of the switch and is mounted and controlled in such a manner to be free from sparking, noiseless in action, and capable of rapid manipulation. Said keyboard finger-piece or 80 key engages a slide carrying a by-pass pawl, the latter coacting with the contact-arm to first move said arm rearwardly against a spring, tensioning the spring which becomes 85 effective on the further movement of the 90 100

slide and by-pass pawl to release the arm, and then under the force of the released spring tension said arm is thrown into contact with the switch, and thereby closes the circuit. By the use of this by-pass mechanism the operator may hold the finger-key depressed, while the contact-arm may be disconnected by any means, or by the returning carriage and its connections. The finger-key 10 must be returned and the by-pass pawl resume its normal position before the repeating of a switch-closing action can take place. This becomes important in a short return stroke of the carriage, since in such work 15 the operator may have pressed down the key, and the switch may not have been released in some cases.

The disconnection of the contact-arm from the switch by the return of the carriage, to 20 open the circuit, is effected by a stop-member on the carriage which engages a dog carried by the right-hand marginal stop, said dog coacting with a rocking switch-release frame, one end of which carries a depending link, 25 effective to throw out the contact-arm of the switch, at intermediate stations. The contact-arm is released to open the circuit for the final or "O" position of the carriage, by the marginal stop-release lever that is mounted 30 on the carriage.

One feature of the present invention is the provision of a switch-mechanism operated by a finger-key associated with means for preventing a repeat action of the switch contact- 35 arm of the switch-mechanism, while the operator holds the finger-key depressed. The closing of the circuit for the second cycle of operation can take place only after the return of the finger-key.

40 The typewriter-carriage is advanced step by step in the usual manner. When it is desired to return the carriage, a key is depressed which closes a carriage-returning motor-circuit. The motor is at one end of a carriage- 45 driving train. Said train is made up of three sections. The first section is at the motor end of the train; the third section is at the carriage end of the train; and the second section is intermediate the first and third sections. Each section is in the nature of a 50 shaft. When the circuit is closed through the motor, as aforesaid, the motor-section of the train revolves, while the other two sections of said train remain momentarily stationary. The motor-section at this time 55 tensions or winds a spring, one end of which is connected to the intermediate section of the train. Hence the motor tends to rotate said intermediate section. The latter, however, 60 is permanently controlled by means of a regulatable friction-device, which exerts a drag, so that this intermediate section is held back while said spring is being wound by the motor. As soon as enough tension is put into 65 said spring, the intermediate section of said

train overcomes the retardation of said friction-device, and begins to turn. During the ensuing rotation of the first and second sections of the train, the third or carriage-section still remains momentarily motionless; 70 but a carriage-driving clutch is automatically closed by reason of the initial rotation of the intermediate section of the train effected by said motor. The train now operates as a unit, the continued rotation of the motor returning the carriage. 75

During the backward run of the carriage, said friction-device performs a further function of acting as a brake to prevent overspeeding of the motor and carriage. 80

Upon the completion of the return of the carriage, the motor-circuit is automatically opened, whereupon the motor tends to continue in motion idly; but this tendency is opposed by said friction-device or brake, which eventually brings the motor to rest. Thereupon said motor-wound spring (which has been constantly under tension) reacts upon the motor, giving it a backward rotation, and the motor now acquires a certain momentum. 90 This backward rotation of the motor is independent of the second section of said train, which second section remains temporarily stationary. The independent backward rotation of the motor is terminated by reason of the interengagement of parts upon the first and second sections of the train, so that both said sections revolve backwardly together as a unit while the motor continues its idle backward rotation. During this idle 100 backward rotation of the first and second sections of the train and the motor, the third or carriage section at first remains stationary, so that the effect is to open said clutch between the second and third sections, thus 105 freeing the carriage for the next line of typing.

110 It will be understood that when the motor-circuit is again closed, the load on the motor is relatively light, because it can start, and then rotate a substantial distance, before it picks up said spring and begins to tension the same. The tensioning of the spring puts a further load upon the motor; and finally the driving of the carriage puts a maximum 115 load thereon, so that the loading of the motor is gradual.

120 A further feature is a provision for enabling easy removal of the carriage-rack-bar.

Other features and advantages will herein- 125 after appear.

Figures 26 to 30, inclusive, show in detail (perspective views) the wiring connections

between the motor-base and the intermediate frame.

Figure 31 is a perspective view, partly in section, of the worm-wheel, a friction spring plate with adjusting screws for regulating the tension of the plate, and a locking means to hold the screws in their adjusted position.

In the practice of my invention, a carriage 10 of an Underwood typewriting machine in which the invention is embodied is supported in the well-known manner to travel along the machine for letter-spacing on a rear rail 8 and a front rail 9 secured on the main frame 11.

For returning the carriage there is provided a carriage-rack-bar 13 which meshes with a pinion 14 driven by a motor 15, and suitable clutch-mechanism is interposed between the motor and pinion, so that the pinion may be either connected to the motor or disconnected therefrom.

Referring to Figures 1 to 4 and 10 to 13, it will be seen that the motor 15 at the rear of the machine is attached to a bracket 16 of a housing 17 secured to a base-plate 18 supported on an intermediate frame 19 of the main frame 11.

The intermediate frame 19 may be fastened to the main frame without boring into or machining the frame, this being done by removing the usual fastening screws from the lower frame parts, and substituting four bushings, the top of the bushings serving as a foundation. Four screws 20, passing through the bushings, hold the frame in place.

A lateral extension of the frame 19 provides a suitable platform on which to set the base-plate 18 on which are mounted as a unit the motor and driving train, including the clutch and clutch-actuator for returning the carriage.

The motor 15 is fastened to the bracket 16 of housing 17 by screws 21, and the motor-shaft 22 will be in axial alignment with and drive a worm-shaft 23 passing through bearings of the housing 17, between which is a worm 24 secured to the shaft, driving a worm-wheel 25.

The latter is mounted on a shaft 26 also mounted in the housing 17. The shaft 26 extends forward of the housing through a suitable bearing and carries on its free end a pair of clutch-members, one 27 being fast on the shaft 26 and having clutch-teeth (being the driving member), and the other being a shiftable clutch-member 28 also having clutch-teeth.

This member 28 is freely fitted to the shaft 26 to rotate therewith when in clutch engagement, and free to rotate on said shaft when out of clutch engagement. The shiftable member, preferably an integral structure, is in the form of a sleeve having at one end an enlarged head with pinion-teeth 29 on its periphery to mesh with the carriage-rack 13, and clutch-teeth on its face

for engaging the teeth of the fixed clutch-member. At the opposite end the sleeve has

120
125
130

a flanged ring 30 by means of which it is shifted to clutch position by an actuator 31 in the train.

The motor-shaft 22 and worm-shaft 23 are connected by a yielding driving coupling 32, the coupling being preferably a section of a coil spring 33 secured at each end to fittings 34 having recesses 35 therein to fit projections 36 on the ends of the shafts 22 and 23 10 by means of which the worm-shaft 23 is driven.

The opposite end of the worm-shaft 23 is provided with a clutch-actuating cam 37 frictionally mounted on the shaft. This cam 15 is of plate form having a cam projection 38, and is held between a pair of friction washers 39, preferably of fiber, and a pair of steel washers 40, all of which, including the cam, are bored to fit the shaft 23. The steel 20 washers are located, one on each side of the fiber washers. The washers are forced against the bearing 41 of the housing by a regulatable friction adjusting means, including a spring 42 fitting over the end of the 25 shaft 23. The inner end of spring 42 engages the outer steel washer of the set, and is held thereto by a cap 43 enclosing the spring. The cap is held by a screw 44 entering the shaft end, which tightens the cap 43 to the shaft 30 with the spring compressed therein and thereby holds the cam under friction to rotate with the shaft, so that the cam may perform the work of shifting the actuator 31, and thereby shift the clutch-members into engagement. The cam is prevented from further rotation by contact with the actuator, and will remain stationary on the rotating 35 shaft until the motor is at rest.

When it is desired to regulate the tension 40 on the friction members of the cam a washer 45 is selected from washers of varying thicknesses and is inserted between the bottom of the cap 43 and the spring 42, increasing or decreasing the compression of the spring, and 45 thereby the friction on the cam. The increasing of the friction on the cam 37 is effective to put greater work on the yielding spring coupling 32, which results in winding up the spring 33 more or less when the motor 50 is running. Moreover, when the cam 37 is in contact with the actuator 31 and has moved the clutch-members to their engaging position for returning the carriage, there is established a more forceful reverse of the motor-shaft by the reaction of the spring 33 to 55 normal relation with the worm-shaft when the motor is stopped. Further, the speed of the motor is retarded by this increase of friction on the cam when the cam is engaging 60 the actuator and held against rotation, acting as a brake on the motor, and thereby the return speed of the carriage is put under control.

The actuator 31 for engaging the clutch- 65 flanged ring 30 is pivoted at 46 in the hous-

ing at one side and under the bearing in which the shaft 26 of the clutch is mounted. The actuator at one side of the pivot 46 is extended and has a bent end 47 to be engaged by the cam 37, and on the other side of the pivot is also bent in U form to provide for ears wherein a stop-screw 48 is fitted to limit the motion of the actuator in one direction. In the other direction, or at the normal position of the actuator, it is held against the 70 housing by the pressure of a spring 49 between the clutch-members 27 and 28, which holds the clutch-members out of their engaging position, as well as returns the actuator 31. The flanged ring 30 exerts pressure 75 against a friction roll 50 of the actuator located on the extended portion just in front of the flanged ring between the pivot 46 and the cam-engaging end 47. It will be apparent that the motor 15, in driving the train just referred to, will exert its power upon the worm-shaft 23, which freely rotates therewith, and thereby the worm 24 will drive the worm-wheel 25 and shaft 26 rotating the driving clutch-member 27; the shiftable 80 clutch-member 28 being at this time held out of action by its spring 49.

When the worm-shaft 23 has revolved to bring the frictional cam 37 with its cam projection 38 to engage the actuator end 47, the friction roll 50 engages the flanged ring 30 moving the clutch-members 27 and 28 together. The cam 37 is prevented from traveling further with the shaft due to the projection 38 on the cam being too long to rotate past the actuator end 47. The cam therefore remains stationary on the shaft while the shaft continues to rotate, which provides an added load on the motor. This tends to wind up the spring 33 of the yielding coupling 32 105 until the friction of the cam 37 is overcome by this increase in winding up of the spring, and the carriage will be returned by rack 13 and pinion 14.

When the motor is stopped, the cam 37 still 110 engages the actuator. The motor, however, is quickly reversed, due to the unwinding of the spring coupling member 32, which brings back to normal relation the motor-shaft 22 and worm-shaft 23, and causing thereafter 115 the motor to carry therewith (also in reverse) the worm-shaft 23. The cam 37 hence backs away from the actuator end 47, again coming into contact with the actuator end 47 but in the reverse direction. This limits the 120 reverse motion of the motor, freeing the clutch-member 28 by the spring 49; and the flanged ring 30 forces the actuator to its normal position, completing the cycle. This reverse motion of the motor and worm-shaft is not 125 so rapid as to cause a jar, since the armature of the motor is heavy, and the return to normal position of the two shafts is cushioned. The slight rotation backward of the worm-shaft 23 also starts in reverse motion, 130

but very slightly, the worm-wheel 25 and shaft 26, thereby relieving the driving strain on the clutch-teeth of the clutch-member 28, which latter will readily respond to the spring 49 to return the clutch-member 28 to its normal position.

The distance between the carriage-rack 13 and the top of the platform of the intermediate frame 19 may vary, which will result 10 in improper meshing of the pinion 14 carried by the housing 17 of the base-plate 18 with the carriage-rack 13. To compensate for this, between the top of the base-plate 18 and under the bracket 16 which carries the 15 pinion 14, shims 51 of varying thicknesses may be inserted, to raise up the bracket to bring the pinion to proper height position with the rack. The base-plate 18 is held on the intermediate frame 19 by screws 52 20 passing up from under the frame 19. The shim 51 of the proper thickness is placed on top of the base-plate 18 and covered by a finishing plate 53 having depending edges to cover the shim 51 as well as the edges of the 25 base-plate 18. On the top of this plate 53 the bracket 16 is secured by screws 54, which hold the assemblage in position. The motor 15, which is held to the bracket 16, is prevented from vibrating by a screw 58 and 30 check-nut 59 on plate 18. The screw is accessible from beneath and locked by the check-nut on top of the finishing plate and base-plate 18. By this means also, a further 35 fastening is provided for holding the finishing plate 53 to the plate 18.

While the yielding coupling 32 or spring 33 acts as a shock-relieving member in the aforesaid train, it is a feature to provide additional shock-relieving means between the worm-wheel 25 and shaft 26. The inner end of the shaft 26 (see Figure 31) has an enlarged shouldered portion 55 on which the worm-wheel 25 is freely fitted, but it is held in frictional engagement to rotate with the shaft 45 by a spring plate 56 for relieving the shaft of the shock of sudden starting and stopping; the plate 56 being adjustable to increase or decrease the tension by regulating screws 57 entering the shaft end. Between this spring 50 plate 56 and screw-heads, there is a locking plate 60 for preventing the screws 57 from becoming loose or shifting. This plate 60 has bent spring arms 61 arranged to engage 55 with flats 62 of the slotted screw-heads, one spring arm at one side reaching forward to engage a screw-head, and the other arm reversely engaging the other screw-head. By 60 this means the lock-plate serves to lock screws into any regulated position to hold the frictional spring-plate 56 adjusted.

The shaft 26 is held against end motion by a screw 63 and a check-nut 64 located in a cover-plate 65 of the housing, the plate enclosing the worm-gear 25 and the friction 65 plate 56. The point of the screw 63, which

is adjustable, takes a position between the screw-heads 57 on the plate 56 and is locked by the check-nut 64.

Referring particularly to the carriage, the line-spacing and return mechanism is illustrated in Figures 1 to 9, inclusive. The Underwood carriage 10 has at its rear an angular frame 66 extending lengthwise, to which is added a pair of brackets 67 and 68 for supporting the rack-bar 13, meshing with the pinion 14 of the driving mechanism, before described. Bracket 67 is attached to the under side of the frame 66 by screws 69 entering base 70 of the bracket. At the lower end the bracket is bent rearwardly below the carriage-rail 8, forming a bearing member 71, supporting the rack-bar 13. The opposite bracket 68 likewise has a base-portion 73 and a bearing member 74, held by screws 75, and the bracket supports the other end of the rack-bar 13. This bracket 68 carries a line-spacing cam-shaft 82 and gearing connecting with the rack-bar. To prevent the bracket 68 from becoming loose, Figure 2, a plate 76 locks the screws 75. The plate is of spring material and curved, so that its center portion is free from the bracket, except at the threaded holes, and it is further provided with a bore 77 for the reception of a central binding screw 78 by means of which 90 screws 75 are locked. The curved plate serves to spread the screws 75, thereby firmly clamping them. The bracket 68 is further provided with an extension 79 terminating in bent ears 80 and 81, forming bearings for 95 the vertical cam-shaft 82, which is provided at its lower end with a gear-segment 83. The other end of the shaft 82 has fixed thereto a collar 84, having V-shaped teeth 85 to cooperate with teeth 86 on the hub 88 of a detachable cam 87. The hub 88 fits the shaft 82, and is preferably fixed to the cam 87, the cam being of plate form and having a shoulder fitting within a bore 89 of the cam-plate, and being permanently attached. The cam 100 may be held to the collar on the shaft and set into any position rotatively with relation to the gear-segment 83. By means of the teeth on both the collar and cam-hub, the cam may be positioned and held against 105 shifting when clamped by a screw 90. One purpose of shifting the cam 87 from one position to another on the shaft is to engage with a bracket 95 on a line-space slide 91 to make a single or plural line-space shift of the 110 platen.

The usual line-space slide 91 (see Figures 1 and 9), through which is rotated the platen 92 by its connections, such as a pawl 93 and a ratchet 94, is provided with a bracket 95. The arm of the cam 87 engages the front wall 125 of the slide-bracket 95 when shaft 82 is rocked by gear-segment 83. The wall of the bracket is of a sufficient height to be engageable by the cam-arm 87 irrespective of the upper and 130

lower case-shift positions of the platen. A case-shift bar 96 and a roller 97 effect the case-shifting. The usual spring 98 for returning the line-space slide crosses the bracket 95, one end of the spring being hooked on the slide, and the other end on the frame of the carriage, the spring coils being separated about midway of the length of the spring, dividing the spring into two sections, the sections remaining connected with each other by an integral straight length of wire, the latter passing through a cut 99 made in the bracket 95 (Figure 5).

Rack-bar 13 is supported on members 71 and 74 of brackets 67 and 68 in slotted openings 100 and 102 of the rack-bar, one at each end. The slots permit limited longitudinal shift of the rack-bar. To prevent lateral motion of the rack-bar, there is provided a shoulder 103 to which the rack-bar is held by a bent clip 104 attached by screws 105 to bracket 67, the bent clip hooking over the rear of the rack-bar and reaching rearward through the slot 100 of the rack-bar, and permitting free action of the rack-bar longitudinally. By this means the removal of the rack-bar from the bearing 71 is made simple, it only being necessary to loosen the screws 105 and to free the clip, whereupon the rack-bar may be drawn rearward, the bent end of the clip passing out of the slot in the rack-bar. At the opposite end the bracket 68 is also provided with a clip 106 and is attached by two screws 107 to the under side of a bent wall 108 of the bracket 68. This wall 108 is a little higher than the bearing 74 on which this end of the rack-bar rides in its slot. The forward end of the rack-bar is undercut at 109 to the extreme end of the rack-bar. The clip 106 has a bent end similar to the clip 104 and reaches rearward under the cutaway portion and is bent upward to hold the rack-bar on the bearing 74.

The bent wall 108, forward of the screws 107 underneath the wall thereof, carries a pinion 110 which is held by a shoulder screw 111 for free rotation, serving as a guide for the rack-bar against lateral movement between the pinion 110 and the clip 106, thus providing free sliding movement of the rack-bar at this end.

The pinion 110 further acts as an intermediate gear meshing with the segment 83 on the shaft 82, and a short length of rack-teeth 101 on the front of the rack-bar 13 rocks the cam-shaft 82 and the cam 87 to line space the platen. The rack-bar first moves on its bearings 71 and 74 to the end of the slots 100 and 102, whereby the line-space slide is operated, and further movement of the rack-bar by pinion 14 of the driving mechanism moves the carriage rightward. The rack-bar may be quickly detached and replaced.

Referring to Figures 1 and 17 to 22, the switch 115 is located at the left on the bracket

11' of frame 11, above the keyboard and below the supporting rods of the carriage marginal-stop members. A connection from below is made by a key-lever 112 and slide-member 113 to throw in a pivoted switch contact-arm 127 to close the motor circuit. 70

The switch 115 includes a body or frame 116 having an arm 117 held to bracket 11' of frame 11 by screws 118. The body 116 has a guide bracket 119 fastened by a screw 120. 75 The bracket 119 is bent to provide a wall 121, in which there is a guide slot 122 to receive the end of the slide 113, which is further guided for movement by a screw-and-slot connection 123 at the lower part of the switch 80 body 116. Below the frame 116 the slide is bent to make contact with the inner end of the key-lever 112. The upper end of the slide has a shouldered portion 124, between which and the inner side of wall 121 a spring 125 85 is held, and provides for a return motion of the slide after its upward stroke effected by key-lever 112. Bracket 119 extends down and carries a pivot-screw 126 on which is pivoted the switch contact-arm 127, in position to be thrown into contact with a pair of contact members 128 and 129 on a block 130 of insulation. 90

The switch contact-arm 127 is not directly moved into engagement with the contact 95 members 128 and 129. A spring actuator 131 is employed and operated by the slide 113. For this purpose the slide has an extension 132 carrying a bypass pawl 133, the end of which engages a wing 134 of the switch contact-arm 127. Normally the switch contact-arm 127 hangs downward (Figure 18), and the slide 113 in its lowermost position with the bypass pawl thereon engages the wing 134 on the switch contact-arm 127 and on the 100 upstroke of the slide 113 the spring actuator 131 is forced rearwardly, as in Figure 19 (broken lines), tensioning the spring actuator by the rearward action of the switch-arm, which engages a hooked end of the 110 spring actuator 131 and is carried rearward therewith. When the slide 113 approaches the end of its upward stroke, imparted by the key-lever 112, the bypass pawl passes clear of the wing 134 on the switch-arm, the 115 tensioned spring actuator 131 is released, and the arm 127 is thereby thrown into contact position between the contacts 128 and 129. The extension 132 of the slide 113 extends upward, and the top end has a screw 135 around 120 which is coiled a spring 136, one end reaching downward into an opening of the bypass pawl 133 to urge the pawl toward the wing 134 of switch-arm 127, and against a stop 125 137 on the slide 113. The other end of spring 136 is caught over the switch-arm 127, holding it lightly against the hooked end of the spring-actuator 131, thereby preventing the arm from vibrating or jarring into contact or 130 sparking relation with the switch-contact.

members 128 and 129 when the slide 113 is in its normal position. Spring 136, being mounted on the slide 113, travels with same, thus removing the tension on switch-arm 127, when the switch is operated and permits the switch-arm to travel unencumbered by tension of spring 136. In other words, spring 136 holds down the switch-arm only when slide 113 is in normal position.

10 The spring actuator 131 of suitable wire fastens under the screw-head 120 of the bracket 119 by a loop in the spring, both ends of the wire passing into a perforation of the bracket 119, thereby holding the loop from spreading under the screw-head, and forming a fulcrum-point for the tensioning of one end of the spring actuator when being forced backward by the bypass pawl. The spring actuator 131 in its normal position 15 forms a stop for the return of switch-arm 127 when the arm is out of contact.

15 The switch-arm 127 (Figure 17) is insulated from the body of the switch 116 by providing the arm 127 with contact portions 138 and 139 insulated from the arm itself by non-conductive washers 140 and 141, the portion 138 having a head and a stem passing through washer 140, the latter having a reduced part fitting in opening of arm 127, the washer 141 20 fitting on reduced part of washer 140 and the contact 139 on stem of contact 138 held together as in Figure 25 by heading over the stem of contact 138. Insulated block 130, to which the contact members 128 and 129 are 25 attached for engagement with the arm 127 to close the line-circuit, is provided with a head 142 wherein is located a pair of circuit-line connecting bushings 143 held by set screws 144. The bushings are threaded to 30 receive binding screws 145 that serve as terminals to attach line wires. Leaders 146 and 147 are located below the surface at the under side of the block in recesses or channels, one end of the leaders being held to the bushings 35 by screws and carried back through the channels to the opposite end of the block to a similar head perforated to receive a flanged bushing 148 of non-conductive material. The leaders 146 and 147 have bent offset portions 40 also perforated to receive the bushing 148. The leader 146 has its bent offset end folded close to the top of the block, on top of which is located the contact member 128, the position of which will be in a plane with one side 45 of the pivoted contact arm 127. The leader 147 is similarly bent, but provides room between the bent portion for an insulating spacer 149 of such thickness as to provide sufficient space for the proper entrance of the 50 contact arm 127 between the aforesaid member 128 and the contact member 129 to engage with the opposite side of the arm 127 to make the circuit connection. The contact member 129 lying on top of the leader 147, by a screw 55 150 passing through the perforated parts of

leaders 146 and 147, the contact members 128 and 129, and the spacer 149 into the body of the switch frame 116, holds the block and parts together. An additional screw 151 to hold the block to the frame 116 is located at 60 the opposite end of the block, passing between the leaders into the frame 116.

70 The key-lever 112 for operating the slide 113 is preferably mounted on the same pivot center as that of the lock-release lever-shaft 75 of the typewriter on the left side of the machine. The lock-release lever-shaft is shortened and the pivot screw is threaded into the frame 11, and a reduced diameter of the screw passes through the hub of the key-lever and into the end of the lock-release lever-shaft, thereby holding the key-lever in its pivoted position. A flat spring 153 holds the key-lever in its idle position against the frame, as at 154, that is, with the bent end 80 that engages the slide 113 down and clear of the slide.

85 From the foregoing it will be seen on the depression of the key-lever 112, the slide 113 with the bypass pawl thereon is actuated to 90 effect contact between the contact-members 128 and 129 by pivoted contact arm 127, closing the motor circuit. Upon the line-spacing of the platen and the subsequent return of the carriage, the switch-arm 127 is released 95 from the contacts 128 and 129 as the carriage reaches the end of its travel, either at the final stop or at stops provided by the usual shiftable right-hand marginal stop member 155. The latter is mounted on the usual rod 155' 100 of the machine, which has a pivoted dog 156 thereon with a cam-projection on its top engaged by a lug 157 on the carriage to throw the front of the dog downward, which front end rides on a rail of a switch-release frame 158. The latter is mounted to rock on the rod 155' on a pair of corresponding arms extending forward, one at each end of the rail, and an arm reaching rearward in position above the switch. A link 159 is pivoted at 105 159' to the arm and extends down, the free end entering the switch-frame 116, passing into a slot 164 in the wall 121 of the bracket 119. The end of the link is in position to engage the switch-arm 127 at the top thereof, 110 on the rocking of the frame to throw the arm 127 out of contact with the members 128 and 129. The dog 156 may be turned over on its pivot to be out of the path of the lug 157 115 on the carriage, and the carriage will then travel to the full or home position. At this final stop position, the switch-release frame 158 is rocked by the bent end 160 of the right-hand marginal-release lever 161, engaging a cam-projection 162 formed on the 120 end of the rail of the switch-release frame, which rocks the frame, and, as before, throws out the arm 127. To return the frame 158 125 to normal position, and the link 159 clear of the switch-arm 127, a spring 158', coiled 130

about the rod 155', rocks the frame back, the rail of which engages the main frame 11 as a stop.

At Figure 2 the main line connector has a plug-and-socket connection to the hub 165 of bracket 16, one member 166 being stationary in the hub and having two leaders, one leading to a terminal at the top of the motor, and the other leading to a block 167 on the base plate 18 carrying the motor and driving mechanism, and a leader from the other terminal of the motor back to the block 167. The block 167 is carried by the base plate 18 and is formed by two sections, each having semi-circular recesses 168 therein, between which are clamped yielding contact members 169. The latter include ferrule-like members 170 bored to receive the line-connector wires which may be soldered thereto. These ferrule-like members carry rings 171 joined thereto by a short section of a coil-spring 172, the three parts being soldered together, yet by means of the spring the ferrules and rings have a yielding action to and away from each other. The ferrules 170 may be of slightly larger diameter than the rings 171, and when located in the semi-circular recesses of the block are held fast therein by clamping the blocks together by screws passing through the two-part blocks into the base plate 18, in such manner that the rings are not prevented from functioning when in the recesses, and thereby may make proper contact with a pair of contacts 173 carried by the platform-portion of the intermediate frame 19, in which is a block 174, also formed of two parts, including a base 175 and a cap 176. The base 175 has an extended elongated portion 177 that fits within an opening 178 in the frame 19, whereby the top of the extended portion is flush with the top of the platform of the frame 19. Recesses 179 are provided in the extended part of the block wherein the headed contact members 173 are located and held by screws 180 and washer 181. The screw heads serve to join the ends of leaders before leading out of the block 174 through channels formed in both the base and cap. The cap and base are held together by screws that also hold the parts to the under side of the frame 19, the leaders then joining with the block 130 of the switch to the terminal screws 145. By this connection of the line wires, the base plate 18 with the motor and driven mechanism carried thereby is rendered quickly detachable from the intermediate frame 19, the block carrying the yielding contacts 169 being fast on the base plate 18 and removable therewith while the fixed contacts 173 of the block 174 remain on the frame 19, it only being necessary to remove the two screws 52 from under the frame 19.

Briefly stated, the operation of the mechanism is as follows: On depression of the

type-keys the carriage moves step by step, actuated by the usual spring in the drum 12. When the end of the line is reached, the operator depresses the carriage-return key 112. This lifts the slide 113 of the switch, and, through the bypass pawl 133, shifts rearwardly the switch contact arm 127 against spring 131. At a certain point in the slide travel, the bypass pawl releases the arm 127, and the spring 131 throws the arm into circuit between the contact members 128 and 129, whereupon the motor is set in motion. The frictional cam 37 on the two-part shaft 22-23 of the motor 15 engages the clutch-actuator 31 and thereby shifts clutch-member 28 into engagement with the clutch-member 27. The frictional cam 37, as soon as the clutch 28 has made its full engagement stroke, is held against further rotation by contact with the actuator. The cam is then slipping between the friction plates of its mounting and causes the motor-shaft 22 to rotate ahead of shaft 23 by reason of the yielding coupling member 32 between the shafts. This relation is maintained while the clutch-pinion 28, which is now rotating is shifting the rack-bar 13 endwise, thereby rotating intermediate pinion 110 and segment-gear 83, rocking the shaft 82 and its cam 87, and thereby shifting the line-space slide with its pawl to rotate the platen to a new line position. When the rack-bar has line-spaced the platen, it has reached the end of its endwise motion with relation to the carriage, and it now travels with the carriage and returns the same to a predetermined stopping position. At this time, the carriage and rack-bar are stopped at a right-hand marginal-stop position, and the lug 157 on the carriage will engage dog 156, the latter engaging the rail of the switch-release frame 158, rocking its downward; and the link 159 thereon engaging the switch contact arm and forcing it out of its closed-circuit position, whereupon the motor stops. The same operation takes place when the carriage returns to its initial or "O" position, except that the cam 162 on the switch-release frame is engaged by the marginal-stop release lever instead of the dog on the marginal stop. As soon as the motor stops, the forward crowding of the cam 37 against the actuator is relieved by the motor-shaft 22 reversing the motor and shaft by the reaction of the yielding spring coupling, thus bringing shafts 22 and 23 to their normal relation. At this action of reversing the motor-shaft the inertia of which carries also the shaft 23 and cam 37 away from the actuator, the clutch-members are separated by spring 49. The reverse motion of the cam away from the actuator is limited by the cam 37 again engaging the actuator at its under side (see full-line position, Figure 1), whereby the motor is free to be again energized and thereby have a free starting period 130

before the cam is brought to bear against the actuator. The regulating means for the friction between the shaft 23 and cam 37 controls the speed of the motor.

From the foregoing it will be seen that the speed of the motor, the return speed of the carriage, and line-spacing of the platen are adjustably controlled; that the motor-shaft and the carriage-returning worm-driving shaft are joined together by a coupling for a positive transmission of power one to the other; that the coupling includes a closely-wound spiral spring windable in the direction of motor-drive to become resiliently cumulative in storing up motive energy until motion is conveyed to the carriage and the carriage travels in unison with the motor for a carriage-returning movement; that the cumulative storage energy of the spring balances the motive energy required to overcome the resistance of the carriage in a letter-spacing direction and hence becomes a tensioned driving element between the two shafts during the rightward travel of the carriage until the carriage is arrested and the motor cut out and brought to a state of rest; that in the assembly of the two driving shafts, any slight variation in the axial alignment thereof is justified through the flexibility of the spring-coupling; and that the clutching means intermediate the motor and carriage are automatically closed and opened by a rotary movement of the motor while the carriage is at rest.

The motor having stopped, the spring 32, 33 will tend to unwind, and, at a certain time in its unwinding movement, the spring 49 (which is tending to restore the clutch-member 14 and the arm 31, which is being held in position through the spring 32 and the cam 37) will become equalized with 32, 33, and, upon further unwinding of the spring 32, 33, the spring 49 will become stronger, and will thereby be permitted to return said clutch-member 14 and arm 31, said returning parts being cushioned by the cam 37, which is being permitted to return through further unwinding of said spring 32, 33. In this way all of the parts return to their normal position without any strain or jarring.

If, through parts becoming clogged or otherwise obstructed, the switch has failed to operate, after the carriage has been returned, and the electric circuit has not become broken, and the motor has therefore become rigidly connected to the carriage-returning train, any further rotation of said motor would tend to continue to rotate the carriage-returning train; but this would be prevented, since the carriage has already been returned and arrested, and could therefore not move any farther, the result being that some part in said train would break or would cause a great deal of trouble. But, in the present invention, this is prevented, since the wheel

25 is frictionally held to the shaft 26. Should the switch fail to break the electric circuit and the motor continue to run, the toothed wheel 25 will continue to rotate without rotating the shaft 26, due to its frictional connection, and thereby prevent any part from breaking. The motor will continue running until the operator notices that something is not right, and operates the switch-button usually provided on the typewriter, to break the electric circuit; thus avoiding damage.

Variations may be resorted to within the scope of the invention, and portions of the improvements may be used without others.

Having thus described my invention, I claim:

1. In a typewriting machine, the combination with a platen and a letter-feeding carriage therefor, of power-means for returning the carriage, including a motor-shaft and a driven shaft, the driven shaft carrying a cam frictionally mounted thereon, and including regulating means for varying said friction, and clutch-mechanism between the carriage and motor including an actuator engageable by the cam to effect a clutch-engagement therewith, and during said engagement also control the speed of the motor and return travel of the carriage.

2. In a typewriting machine, the combination with a revoluble platen and a letter-feeding carriage therefor, of power-operated means for line-spacing the platen and returning the carriage, including a motor, a speed-reducing element driven by the motor, an electric switch for starting and stopping the motor, a finger-key, operatively connected with a switch-arm to close the circuit, to energize the motor, clutch-mechanism including a driving and driven clutch-member, both carried by the speed-reducing element and controlled in their operation by means carried by the motor-shaft to effect coupling and uncoupling of the clutch-members, one of said members being a pinion in operative connection with a rack-bar slidably mounted on the carriage for a limited movement, said rack-bar having a geared connection with a cam-shaft and cam thereon likewise mounted on the carriage to engage a lug on a line-space-actuating slide of the carriage and thereby bring the platen to a new line-position, the carriage being returned to its line-starting position by further motion imparted to the rack-bar by the clutch-pinion, and means carried by the carriage to engage a rock-frame and thereby throw out the switch-arm and stop the motor.

3. In a typewriting machine, the combination with a revoluble platen and a letter-feeding carriage therefor, of power-means for line-spacing the platen and returning the carriage, said means including a motor and a shaft therefor, a clutch-controlled connection between the motor and carriage, a speed-reducing element driven by the motor, includ-

ing a worm and a shaft therefor and a worm-wheel, a yielding coupling between the motor-shaft and worm-shaft, a worm-wheel shaft rotated by the worm-wheel, a clutch-member fast on said worm-wheel shaft, a pinion loosely but slidably carried by said worm-wheel shaft to have engaging and disengaging connection with the clutch-member, a clutch-actuator for shifting the pinion into clutch-engaging position, means carried by the worm-shaft to rock the clutch-actuator and effect the engagement thereof, a rack-bar carried by the carriage and having a limited endwise movement effective through a geared connection with a line-space slide of the carriage to rotate the platen into a new line-position, the continued movement of said rack-bar returning the carriage to its starting position, a finger-key operatively connected to a switch to energize the motor, and means carried by the carriage to break the circuit at the end of its travel and stop the motor.

4. In a typewriting machine, the combination with a revoluble platen and a letter-feeding carriage therefor, of power-means for returning the carriage, said means including a motor and a shaft therefor, a clutch-controlled connection between the motor and carriage, a speed-reducing element driven by the motor, including a worm and a shaft therefor and a worm-wheel, a yielding coupling between the motor-shaft and worm-shaft, a worm-wheel shaft rotated by the worm-wheel, a clutch-member fast on said worm-wheel shaft, a pinion loosely but slidably carried by said shaft to have engaging and disengaging connection with the clutch-member, a clutch-actuator for shifting the pinion into clutch-engaging position, means carried by the worm-shaft to rock the clutch-actuator and effect the engagement thereof, a rack-bar carried by the carriage effective to return the carriage, a finger-key operatively connected to a switch, to energize the motor, means carried by the carriage to break the circuit and stop the motor, and means between the clutch-members to hold them out of engagement while the motor is at rest.

5. In a typewriting machine, the combination with a revoluble platen and a letter-feeding carriage therefor, of power-means for line-spacing the platen and returning the carriage, said means including a motor, the frame of which is carried by an intermediate frame fixed to the machine, separable, electrical, connecting members carried by the frames, a clutch-controlled connection between the motor and carriage including a rack-bar and a pinion, a speed-reducing element driven by the motor, including a worm and worm-wheel, a yielding coupling between the motor and its shaft and worm and worm-shaft driven thereby, a worm-wheel shaft rotated by the worm-wheel, a clutch-member fast on said worm-wheel shaft, a pinion with

clutch-teeth loosely and slidably carried by said worm-wheel shaft to have engaging and disengaging connection with the clutch-member fast on said shaft, a clutch-actuator for shifting the pinion into clutch-engaging position, means carried by the worm-shaft to rock the clutch-actuator and effect the engagement of the clutch-members including a cam frictionally controlled, regulating means for increasing or decreasing the friction which regulates the clutch-engaging action, the speed of the motor and thereby the return of the carriage, a rack-bar carried by the carriage and mounted to have a limited endwise movement with relation thereto, a geared connection to a line-space slide carried by the carriage-frame, effective to rotate the platen into a new line position, said geared connection including a vertical shaft, a gear-segment, an intermediate pinion, teeth on the rack-bar of the carriage, a cam on the vertical shaft to coact with a lug on the line-space slide of the carriage and thereby line-space the platen, the continued movement of the rack-bar returning the carriage to its line-starting position, a finger-key operatively connected to a switch to energize the motor, and means carried by the carriage to break the circuit and stop the motor.

6. In a typewriting machine, the combination with a revoluble platen and a letter-feeding carriage therefor, of power-means for line-spacing the platen and returning the carriage, said means including a motor and a shaft therefor, a clutch-controlled connection between the motor and carriage, a speed-reducing element driven by the motor, including a worm and a shaft therefor and a worm-wheel, a yielding coupling between the motor-shaft and worm-shaft, a clutch-actuating cam frictionally carried by said worm-shaft and embodying means for regulating said friction, a worm-wheel shaft rotated by the worm-wheel, said worm-wheel having a shock-relieving spring plate interposed between adjusting means which drives said worm-wheel shaft, a clutch-member fast on said worm-wheel shaft, a pinion loosely but slidably carried by said shaft to have clutch-engaging and disengaging connection with the fixed clutch-member, a clutch-actuator for shifting the pinion into clutch-engaging position by the aforementioned actuating cam to effect the engagement of said clutch-members, a rack-bar carried by the carriage and having a limited endwise movement with relation to said carriage, said movement effective through a geared connection to line-space the carriage-platen by rotating the platen into a new-line position, the continued movement of the rack-bar imparted thereto by the pinion returning the carriage to its normal or line-starting position, a finger-key operatively connected to a switch to energize

the motor, and means carried by the carriage to break the circuit and stop the motor.

7. In a typewriting machine, the combination with a revoluble platen and a letter-feeding carriage therefor, of power-means for line-spacing the platen and returning the carriage, said means including a motor and a shaft therefor, a clutch-controlled connection between the motor and carriage, a speed-reducing element driven by the motor, including a worm and a shaft therefor and a worm-wheel, a yielding coupling between the motor-shaft and worm-shaft, a clutch-actuating cam frictionally carried by said worm-shaft and embodying means for regulating said friction, a worm-wheel shaft rotated by the worm-wheel, said worm-wheel having a shock-relieving spring plate interposed between adjusting means which drives said worm-wheel shaft, regulatable by screws to increase or decrease the tension of said spring plate and means to hold the screws in their regulated position, a clutch-member fast on said worm-wheel shaft, a pinion loosely but slidably carried by said shaft to have clutch-engaging and disengaging connection with the fixed clutch-member, a clutch-actuator for shifting the pinion into clutch-engaging position by the aforementioned actuating cam to effect the engagement of said clutch-members, a rack-bar carried by the carriage and having a limited endwise movement with relation to said carriage, said movement effective through a geared connection to line-space the carriage-platen by rotating the platen into a new line-position, the continued movement of the rack-bar imparted thereto by the pinion returning the carriage to its normal or line-starting position, a finger-key operatively connected to a switch to energize the motor, and means carried by the carriage to break the circuit and stop the motor.

8. In a typewriting machine, the combination with a revoluble platen and a letter-feeding carriage therefor, of power-operated means, including a motor, a speed-reducing element yieldingly coupled to the motor, the motor-shaft of which forming one part of a two-part driving shaft between the driven element and motor by a yielding coupling in the form of a helical spring, clutch-mechanism controlled by the yieldingly-driven element including a rack-bar, a pair of clutch-members, a pinion in engagement with the rack-bar, the latter controlled by the clutch-mechanism to transmit return-motion to the carriage, and gearing operated by the rack-bar to rotate the carriage-platen to a new line-position, electrical means for controlling the motor, including a switch, and a circuit maker and breaker controlled by a finger-key to close the circuit, and means carried by the carriage to open the circuit at the extreme return position of the carriage or predetermined station along the return thereof.

9. In a typewriting machine, the combination with a traveling carriage, of a motor having controlling means, carriage-driving means including a toothed clutch-mechanism normally inoperative between the motor and the carriage, motor-rotated frictionally operating means for forcing the teeth of the clutch into a driving interlock to start the carriage, after an interval of motor rotation, and means between the toothed clutch-members operative to separate said clutch-members to release the carriage when the motor stops, said motor-drive being interrupted by means on the carriage actuating a connection to the motor-controlling means. 80

10. In a typewriting machine, the combination with a revoluble platen, a letter-feeding carriage therefor and writing instrumentalities, including a type-bar segment and a supporting frame therefor, of a motor, means for controlling the motor, mechanism driven thereby including a yielding coupling-member between a two-part shaft of the motor and said mechanism, a frictionally-driven cam on the two-part shaft 90 of the mechanism to actuate an actuator effective through suitable clutch-members to start the carriage on return travel, and means between the clutch-members to separate each other when the motor stops, said motor being 95 stopped by a lug on the carriage actuating a rock-frame having a connection to open a circuit of the motor-controlling means.

11. In a typewriting machine, the combination of power-means for returning the carriage to a new line-starting position, including a driving and a driven member, said members being coupled by a yielding connector whereby a normal and a relatively rotatable relation is established between said 105 members, means including a cam in regulatable frictional engagement carried by the driven member, and means between the carriage and the driven member including a clutch brought into operative engagement by the said cam-means to return the carriage.

12. In a typewriting machine, the combination of power-means for returning the carriage to a new line-starting position including a driving and a driven member, said 115 members being coupled by a yielding connector whereby a normal and a relatively rotatable relation is established between said members, means including a cam in regulatable frictional engagement carried by the driven 120 member, means between the carriage and the driven member including a clutch brought into operative engagement by the said cam-means to return the carriage, together with electrical means including a switch-mechanism manually controlled to start the power-means, and means carried by the carriage to automatically stop the power. 125

13. In a typewriting machine, the combination of power-means for returning the 130

- carriage to a new line-starting position, including a driving and a driven member, said members being coupled by a yielding connector whereby a normal and a relatively rotatable relation is established between said members, means including a cam in regulatable frictional engagement carried by the driven member, means between the carriage and the driven member including a clutch 5
 10 brought into operative engagement by the said cam-means to return the carriage, and means carried by the carriage to stop the power at the end of its return travel whereby on the stopping of the power the yielding connector effects a return to normal relation of the driving and driven members, the frictional cam relaxing its pressure against the clutch-members, and releasing the clutch-members by a spring between the same.
 15
 20 14. In a typewriting machine, a power-driven line-spacing and carriage-return means including a switch to energize a motor, a key having connections to actuate the switch, a line-spacing and carriage-returning train of mechanism driven by the motor, including a clutch and clutch-closing means controlled by said train through a rack-bar on the carriage to return the same, and means on said carriage to engage a dog pivoted to a shiftable carriage-stop, said dog engaging a switch-release frame, having a connection which opens the switch to stop the motor and prevent repeat action independently of the depressed key.
 25
 30
 35 15. In a typewriting machine, a power-driven line-spacing and carriage-return means, including a switch manually operated to energize a motor, a line-spacing and carriage-returning train of mechanism driven by the motor, including a clutch and clutch-actuating means controlled by said train through a rack-bar on the carriage to return the same, and means on said carriage to engage a dog pivoted to a shiftable carriage-stop, said dog effective to rock a switch-release frame, a connection of which opens the circuit to stop the motor, said pivoted dog shiftable out of the path of said means on the carriage whereby a second means on the carriage will rock the switch-release frame and open the circuit at a full returned stop position of the carriage.
 40
 45
 50
 55 16. In a typewriting machine having a motor-driven line-spacing and carriage-return mechanism, including a motor and a driving train, said train providing a driving shaft, a worm and worm-shaft, a yielding coupling connected with said shafts, a worm and a worm-wheel driven by said worm, a shock-relieving regulatable friction-plate on said worm-wheel to make a driving connection with the shaft on which it rotates, adjusting screws for regulating said friction-plate, and means for holding said adjustment fixed.
 60
 65
 70
 75 17. In a typewriting machine, the combination of power-means for returning the carriage to a new line position, including a motor, a train of mechanism rotated by said motor including a normally-open clutch-mechanism, a geared connection between said clutch mechanism and the carriage, and an actuator frictionally operated by the rotation of said train to close the clutch-mechanism after the motor has been rotated a predetermined extent and to maintain the clutch in closed condition during the motor operation.
 80
 85 18. In a typewriting machine, the combination of power-means for returning the carriage to a new line position, including a motor and a train of mechanism driven thereby, said train including a clutch-actuator, a pair of clutch-members held out of engagement by a spring which also holds the actuator in its inoperative position, and a cam frictionally carried by a shaft of said train, said cam, on the driving of said motor, engaging said actuator and thereby making engagement with said clutch-members, one of said clutch-members having a connection with a rack on the carriage by which it is returned.
 90
 95
 100 19. In a typewriting machine, the combination of power-means for returning the carriage to a new line position, including a motor, a driving shaft, a driven shaft, and a train of mechanism which includes a clutch-actuator and a pair of clutch-members, one of said clutch-members having pinion-teeth meshing with a rack of the carriage, and means including a cam frictionally carried by the driven shaft for engaging the clutch-actuator to effect clutch-connection and thereby return the carriage.
 105
 110 20. In a typewriting machine, the combination of power-means for returning the carriage to a new line position, including a motor, a driving shaft, a driven shaft, a yielding coupling between the shafts, and a train of mechanism which also includes a clutch-actuator and a pair of clutch-members, one of said clutch-members having pinion-teeth meshing with a rack of the carriage, and means including a cam frictionally carried by the driven shaft for engaging the clutch-actuator when the motor is driving to effect clutch-connection and hold said connection while the carriage is being returned.
 115
 120 21. In a typewriting machine, the combination of power-means for returning the carriage to a new line position, including a motor, a driving shaft, a driven shaft, a yielding coupling between the shafts, the yielding of which changes the rotative relation of said shafts producing a spring tension between said shafts, and a train of mechanism which includes a clutch-actuator and a pair of clutch-members, one of said clutch-members having pinion-teeth meshing with a rack of the carriage, and means including a cam frictionally carried by the driven shaft for en- 125
 130

gaging said clutch-actuator to effect clutch connection, said clutch-actuator holding the clutch-members in clutch engagement by the frictional cam while the motor is driving the train, said yielding coupling, on the stopping of the motor, relaxing from said spring tension, reversing the rotation of the motor while said cam still engages the actuator, carrying in reverse rotation therewith the driven shaft 5 and the cam thereon, and freeing both the actuator and clutch-members.

22. In a typewriting machine having a carriage, the combination of means for returning the carriage to a new line-position, including a motor and a motor-control, a normally open clutch-mechanism intermediate the carriage and the motor, a rotatable driving train of mechanism intermediate the clutch-mechanism and the motor, a rotary 10 yieldable cumulative element in the motor-driven train of mechanism, tensioned by the driving rotation of the motor to store up energy equivalent to the energy required to overcome the carriage-returning resistance, 15 and a cam frictionally driven by the motor-driven train of mechanism to close the clutch-mechanism and render the driven train effective to return the carriage, said cumulative element at the end of the carriage-return 20 movement becoming reactive, to reverse the direction of rotation for the motor-driven train and the cam, and release the closed clutch-mechanism and free the carriage.

23. In a typewriting machine, the combination of a traveling carriage, a motor-driven shaft, a shaft-driven train of mechanism intermediate the motor-shaft and the carriage, including a normally open clutch, a coupling joining the train-driving shaft with the motor-driven shaft, and a clutch-controlling mechanism intermittively driven by said train of mechanism to close the clutch during a motor-rotation of predetermined extent to return the carriage for a new line, said 25 coupling having cumulative characteristics for storing up energy derived from the initial rotation of the motor-driven shaft before motion is conveyed to the carriage, said accumulated energy in the coupling becoming 30 effective, after the return of the carriage, to release the clutch-controlling mechanism and free the carriage.

24. In a typewriting machine, the combination of a traveling carriage, a motor-driven shaft, a shaft-driven train of mechanism intermediate the motor-shaft and the carriage, including a normally open clutch-mechanism, a coupling joining the train-driving shaft with the motor-driven shaft, and a clutch-controlling mechanism including a cam, intermittively rotated by said train of mechanism and effective to close and frictionally hold the clutch-mechanism during a motor-rotation of predetermined extent to return 35 the carriage for a new line, said coupling

including a spring wound in the direction of motor-rotation to be wound up by the motor before motion is conveyed to the carriage, the wound-up coupling becoming automatically effective at the end of a carriage-return 70 movement to reversely rotate the cam and release the clutch-mechanism from the carriage.

25. In a typewriting machine, the combination of a traveling carriage, a motor-driven shaft, a shaft-driven train of mechanism intermediate the motor-shaft and the carriage, including a worm, a worm-gear and a worm-gear shaft, having a normally open clutch-device connectible with the carriage, a clutch-control device including a cam mounted to rotate with the shaft to close the clutch-mechanism, means to arrest the cam after a clutch-closing rotation and hold the cam stationary during the subsequent carriage-returning rotation of the worm-gear shaft, and a coupling intermediate the motor-shaft and the shaft of the train of driving mechanism, said coupling having a power-accumulating characteristic during the rotation and subsequent 80 arrest of the clutch-closing cam that becomes automatically effective at the end of the carriage-return movement to reversely rotate the motor and the clutch-controlling cam to release the carriage from the motor. 85

26. In a typewriting machine, a carriage, a motor, and a motor-driven carriage-returning mechanism having clutch-members, and automatic means controlled by rotary movements of the motor for connecting the motor 100 to the carriage, maintaining said connection during the rotation of the motor, and disconnecting the carriage from the motor upon the conclusion of the motor operation.

27. In a typewriting machine, a carriage, a motor, a motor-driven carriage-return mechanism having clutch-members, and automatic means rotatable with the motor in its driving direction of rotation for making and maintaining a clutch relation between the motor 105 and carriage and automatically effective at the end of the motor-driven operation to disconnect the clutch-relations of the carriage and motor by driving the motor in a reverse direction. 110

28. In a typewriting machine, a carriage, a motor, and a motor-driven carriage-returning mechanism having clutch-members, and automatic means rotated oppositely by the motor to be self-connecting with the carriage throughout the rotation of the motor in one direction and self-disconnecting from the carriage when the motor rotates in a reverse direction. 120

29. In a typewriting machine, the combination of a traveling carriage, a motor, connections between the motor and the carriage for automatically returning the latter to line-starting position, said connections including interlocking clutch-members, one member 125

rotatably connected with the carriage, and the other member rotatably connected with the motor, and means brought into action through the rotation of the motor after the rotation of the motor has been established 5 for shifting one member into interlock with the other member.

30. In a typewriting machine, the combination of a traveling carriage, a motor, connections between the motor and the carriage 10 for automatically returning the latter to line-starting position, said connections including interlocking clutch-members separated by a clutch-opening spring, one member rotatably connected with the carriage, and the other member rotatably connected with the motor, and means for shifting one clutch-member 15 into interlock with the other clutch-member through the rotary movement of the motor, said means becoming operative to release the interlocked clutch-members to their clutch-opening spring when the rotary direction of the motor is reversed.

31. In a typewriting machine, the combination of a traveling carriage, a motor, connections between the motor and the carriage 20 for automatically returning the latter to line-starting position, said connections including interlocking clutch-members separated by a clutch-opening spring, one clutch-member 25 rotatably connected with the carriage, and the other clutch-member rotatably connected with the motor, means for shifting one clutch-member into interlock with the other clutch-member through the rotary movement of the motor, said means becoming operative to release the interlocked relation of 30 said clutch-members to their clutch-opening spring when the rotary direction of the motor 35 is reversed, and means for automatically reversing the direction of motor-rotation.

32. In a typewriting machine having a carriage, the combination of means for returning the carriage for the beginning of a new line, 40 including a driving motor, reactionary means wound up by the motor, a clutch-mechanism connectible with the carriage and driven by the motor through the reactionary means, and means for silencing the motor at the end 45 of a carriage-returning rotation thereof, said clutch-mechanism automatically rendered inoperative by the reactionary means reversely rotating the motor after the motor has been silenced.

55. 33. In a typewriting machine, the combination of a traveling carriage having a toothed rack, a motor, and carriage-driving connections between the motor and rack for returning the carriage to initial line-starting 60 position, said connections including a worm, and a worm-wheel driven thereby, and also including a pinion always in train with the rack, and a friction drive between the worm-wheel and the pinion, a clutch-member all 65 ways in train with the motor, an element

rotated by the motor, and an actuator operated by the rotation of said element and effective both to shift the pinion into clutching engagement and to maintain such engagement with the motor-driven clutch-member 70 to rotate the pinion and drive the rack to return the carriage.

34. In a typewriting machine, the combination of a traveling carriage having a toothed rack, a motor, and carriage-driving 75 connections between the motor and rack for returning the carriage to initial line-starting position, said connections including a pinion always in train with the rack, a clutch-member always in train with the motor, an element rotated by the motor, an actuator operated by the rotation of said element and effective both to shift the pinion into clutching engagement and to maintain such engagement with the motor-driven clutch- 80 member, to rotate the pinion and drive the rack to return the carriage, said actuator carrying stop-means to limit the motor-driven shaft of the pinion, and having anti-friction means bearing against the rotating 85 pinion to enable said rotating member to maintain the clutch relations between said pinion and said clutch-member.
